UNITED STATES PATENT OFFICE.

LIBORIUS SENGE, OF CRESCENT SPRINGS, KENTUCKY, ASSIGNOR TO THE GLOBE-WERNICKE COMPANY, OF CINCINNATI, OHIO, A CORPORATION OF OHIO.

POST-BINDER.

No. 902,612.

Specification of Letters Patent.

Patented Nov. 3, 1908.

Application filed May 21, 1908. Serial No. 434,150.

To all whom it may concern:

Be it known that I, LIBORIUS SENGE, a citizen of the United States, residing at Crescent Springs, in the county of Kenton and State of Kentucky, have invented certain new and useful Improvements in Post-Binders, of which the following is a full, clear, and exact description, reference being had to the accompanying drawing, forming part of this specification.

My invention relates to binding files or loose leaf binders generally known to the trade as post binders wherein any number of letters, bills or other sheets may be bound; and it has for its object the production of a binder of this class which is simple in construction, cheap to produce and exceedingly efficient in action.

The novelty of my invention will be hereinafter more fully set forth and specifically pointed out in the claims.

In the accompanying drawing; Figure 1 is a perspective view of a post binder embodying my invention, and partly filled with sheets. Fig. 2 is a sectional view showing the general arrangement of the parts of the clamping mechanism.

The same numerals of reference are used to indicate identical parts in both the figures.

In the drawing 1 represents the usual or any suitable base provided with and carrying the posts 2 2. The posts pass through suitable openings in the cover 3 which is of the usual construction. Secured to the upper surface of the cover 3 is a plate 4 provided with openings registering with the openings in the cover 3 for the passage therethrough of the posts 2 2, and this plate 4 has loosely riveted to it, as at 5, a pair of clutches 6, one for each post, said clutches having their adjacent ends normally pressed toward the plate 4 by the blade spring 7 which is riveted, as shown, to the plate 4 at or near its middle.

The clutches 6 are perforated to permit of the passage of the posts 2 2 therethrough and are of such shape at these perforations that when tilted or angled in certain ways with relation to the posts a pinching action is set up to prevent movement of the clutches and consequently the cover along the posts in a direction away from the bottom 1, and that when tilted or angled in other direc-

tions with relation to these posts the clutches and consequently the cover are released so that they may be freely moved along the posts. The normal tendency of the clutches is to engage the posts, this tendency being due to the action of the blade spring 7 exerting its influence on the clutches and the released position of the clutches is secured by pressing downward upon the outer free ends of the clutches to overcome the resistance of the blade spring 7.

In service the cover 3 is removed from the binder by grasping the edges thereof adjacent to the clutches and at the same time depressing the clutches thereby releasing them from the posts whereupon the cover is readily removed from the posts. The papers or sheets to be filed having been suitably perforated are then strung upon the posts and the cover replaced thereupon and snugly pressed down upon the contents of the binder. Immediately upon releasing the clutches the action of the blade spring 7 becomes effective to cause the engagement of the clutches with the posts to retain the cover in the position it occupied when the clutches were released.

By reference to Fig. 2 the position of engagement of the clutches is shown in solid lines and the position of disengagement of one thereof is shown in dotted lines on the right hand side of the figure.

Having thus fully described my invention I claim:

1. In a post binder, the combination of a base, posts carried thereby, a cover adapted to be strung upon said posts, tilting clutches carried by said cover and adapted to engage said posts, an extension upon each of said tilting clutches beyond their point of engagement with said posts, said extensions being formed to receive and be alined by a spring, a spring secured to said cover at or near its middle and having its free ends engaging the extensions of said tilting clutches to cause the engagement thereof with said posts, substantially as described.

2. In a post binder, the combination of a base, posts carried thereby, a cover adapted to be strung upon said posts, tilting clutches carried by said cover and attached thereto at points in line with and a greater distance apart than said posts, said clutches being

adapted to engage said posts, an extension
upon each of said tilting clutches beyond
their point of engagement with said posts,
said extensions being formed to receive and
5 be alined by a spring, a spring secured to
said cover in line with and between said
posts and having its free ends engaging the

extensions of said tilting clutches to cause
the engagement thereof with said posts, sub-
stantially as described.

LIBORIUS SENGE.
